UNITED STATES PATENT OFFICE.

JOHN BRICKEN, OF CHICAGO, ILLINOIS, ASSIGNOR, BY DIRECT AND MESNE ASSIGNMENTS, TO BURROUGHS ADDING MACHINE COMPANY, OF DETROIT, MICHIGAN, A CORPORATION OF MICHIGAN.

CALCULATING-MACHINE.

1,119,061.

Specification of Letters Patent.

Patented Dec. 1, 1914.

Application filed November 27, 1909, Serial No. 530,136. Renewed April 3, 1913. Serial No. 758,712.

To all whom it may concern:

Be it known that I, JOHN BRICKEN, a subject of the Emperor of Russia, residing at Chicago, in the county of Cook and State of Illinois, have invented a certain new and useful Improvement in Calculating-Machines, of which the following is a specification.

My invention relates to calculating machines and is in certain respects in the nature of an improvement over the inventions described and claimed in my Patent No. 938,550, issued November 2, 1909, and No. 943,514, issued December 14, 1909.

In my previous machines it is necessary in multiplying by any given digit to press two different figure keys each of which is marked with the same digit, for example, in multiplying by five it is necessary to strike a five units key and then a five tens key.

One of the objects of my present invention is to render it possible to gain the same effect by means of a single key.

Again, in the machine shown in my previous patents the key board and keys are shiftable relatively to the differential members.

One of the objects of my present invention is to produce a machine capable of multiplying without shifting the keys, or pressing them more than once.

Another object of the invention is to produce a machine in which multiplication may be performed commencing from either end of the multiplier.

I obtain my objects by the mechanism illustrated in the accompanying drawings, in which—

Figures 1 and 2 are side elevations in section taken respectively on the lines 1—1 and 2—2 of Fig. 3. Fig. 3 is a plan view taken on the line 3—3, Fig. 2. Fig. 4 is a top plan view showing the figure keys. A portion of the top of the case is broken away at the front of the machine where certain of the parts are shown in horizontal section. Fig. 5 is a front elevation in section taken on the line 5—5, Fig. 1. Fig. 6 is a fragmentary view showing a front elevation in section taken in the line 6—6, Fig. 1. Fig. 7 is a perspective view of the lower portion of one of the figure keys. Fig. 8 is a perspective view of one of the members of the shifting mechanism whereby the differential members are shifted to the position called for by the factor to be used. Fig. 9 is a fragmentary perspective view showing the front end of one of the differential members. Fig. 10 is a perspective view showing the front of one of the actuating segments or actuators and one of the differential members associated therewith.

Similar reference characters denote similar parts throughout the several views.

In the mechanism selected to illustrate the present invention the casing 1 has mounted therein a stationary transverse shaft 2 which serves as a pivot for the actuators 3. There is one of these actuators for each ordinary place in the machine, the number thereof depending upon the capacity of the machine. They are independently rotatable about shaft 2 and are adapted to actuate the computing mechanism in the different ordinal places thereof in the manner well known in calculating machines. They may be conveniently termed the units actuator, tens actuator, hundreds actuator, etc., commencing at the right or lowest ordinal place in the machine.

Associated with each actuator, except the highest and lowest in the machine, are two differential members 5 and 6. These are located on opposite sides of the actuator and are slideable relatively thereto. In the preferred construction the actuators each have two longitudinal slots 3^b through which extend rivets 7 which are slideable in said slots and support the said differential members. The latter are held in position by means of heads 7^a as clearly shown. As the rivets pass through the two differential members on any given actuator it is obvious that said differential members will move in unison and that they will have two movements, one a rotary movement around the shaft 2 as an axis, and the other, a sliding or shifting movement lengthwise of the actuator. The rotary movement produces a corresponding rotary movement of the actuator for actuating the computing wheels (not shown); and the shifting movement is for bringing different points of contact on the differential members into the path of a descending figure key. As an additional support it is desirable to provide rests 3^a on the actuators

along which the lower edges of the differential members may slide. They are best shown in Figs. 1 and 2.

As has been stated, there are two differential members upon each actuator except the highest and lowest. The one on the left side of each actuator (looking from the front as in Fig. 5) will be termed the units differential member; the one on the right, the tens differential member. This is in accordance with the well known table of multiplication, shown, for example, in the earliest of my aforesaid patents and illustrating the fact that the product of any two digits may be expressed by not to exceed two digits, a units digit and a tens digit. The units differential members in my present machine are for representing and setting up the units in such product and the tens differential members are for representing and setting up the tens in such product. Of course some of such products require no tens, but simply units to express them, for example, any digit multiplied by units may be expressed by a single digit and hence in my machine the units actuator possesses but a single differential member and that one is a units differential member.

The figure keys 8 are arranged in vertical rows or columns, one for each ordinal place in the machine. The row at the right are in the units column, the row next to the left in the tens column, etc., the number of rows determining the capacity of the machine. There are nine keys in each row, running from 1 to 9, and each key is adapted to contact the differential members, a units differential member on one actuator and the tens differential member on the next higher actuator. The differential members are so constructed that when thus depressed by a key, the amount of their movement will correspond respectively to the units and tens of the proper product in the table of multiplication above mentioned. To accomplish this the differential members are divided theoretically into nine sections, one for each key and each section theoretically has nine different points of contact where the key may contact it. I say "theoretically" because no point of contact is necessary where zeros occur and in the tens differential members no points of contact are necessary for products which may be expressed by a single digit. The amount of movement of any differential member (and hence of the actuator upon which it is mounted) depends upon which point is contacted, and the point contacted will depend upon the position to which the differential member is shifted lengthwise of the actuator. In other words, a greater or less amount of movement of an actuator may be produced upon the action of any given key by shifting the differential members which said key will contact; and

hence it will be clear that the position of the differential members becomes a factor in the amount of movement of the actuators and hence of the computing mechanism. This movement of the differential members 70 I produce by means of factor keys 9 which, in the present instance, are arranged at the left side of the machine in a vertical row parallel to the figure keys. There are eight of these factor keys running from 2 to 9, as 75 best shown in Fig. 4. Various forms of connection between the factor keys and the differential members may be devised without exceeding the scope of my invention, but in the form of machine selected for illustration 80 said factor keys are arranged so that any one of them is operative upon the approximately horizontal arm 10 of a bell crank lever which is rigidly secured to the rock shaft 11 and has an approximately 85 vertical arm 12 having a slot 13 at its upper end. By preference, a guide 14 is formed at the free end of arm 10 to confine its movement to a vertical plane. A tension spring 15 secured at one end of arm 12 and at the 90 other end to a fixed rod 16 tends to hold the arm 12 up and the upper end of arm 12 forward toward the front of the machine. An arm similar in construction to arm 12 is rigidly secured to the opposite end of rock 95 shaft 11, as shown in Fig. 3, and is urged by a spring 19 in the same manner as arm 12 is urged by spring 15. Spring 19 is also secured to rod 16. A bar 20 extends across from arm 12 to arm 18, penetrating the slots 100 at the upper ends thereof and forming means for controlling the shifting members 21 to which said bar is connected. Said shifting members are slidably mounted in the brackets 22 and have slots 23 at their 105 lower extremities through which the rivets 7 extend.

From the above it will be apparent that when a factor key is depressed the differential members will all be shifted forward a 110 definite amount, depending upon the key struck.

Suitable guide brackets 24 and 25 are secured in the machine casing for guiding the figure keys and factor keys and said keys 115 are normally held in raised position by means of springs 26.

In operation, let it be assumed that the operator wishes to multiply 234 by 5. He will first depress the factor key "5" which 120 will depress the arm a definite amount and produce a corresponding rotation in the rock shaft 11 which will produce a corresponding amount of rotation in the arms 12 and 18. This causes the links 21 to shift 125 the differential members 5 and 6 along the actuators 3 a definite amount corresponding to the factor 5. After the differential members have been thus shifted by the factor key 5 the operator depresses the figure key 130

"2" in the hundreds column of the machine, then the "3" in the tens column and then the "4" in the units column. The actual results produced may be tabulated thus:—

5	(a)	234	
	(b)	5	
10	(c)	10	
	(d)	15	
	(e)	20	
	(f)	1170	

Line "a" is the multiplicand, "b" the multiplier, lines "c," "d," and "e" the partial products in their proper ordinal places and line "f" the total product. Analyzing this, it means that the figure key 2 will depress the thousands actuator one step and the hundreds actuator no steps. The 3 figure key will depress the hundreds actuator one step and the tens actuator five steps. The 4 figure key will depress the tens actuator two steps and the units actuator no steps. As the movements of any given actuator thus occur successively the aggregate movement of the thousands actuator will be one step, of the hundreds actuator one step, of the tens actuator seven steps and of the units actuator no steps; which corresponds to the total product 1170. In view of the above it becomes obvious that it is immaterial in my machine whether the operator commences at the left or right end 35 of the multiplicand.

I claim as my invention:—

1. A multiplying machine having differential actuators having different points of actuation, and figure keys for operating said differential actuators, said differential actuators being movable to nine different positions relatively to said keys for the purpose described.

2. A multiplying machine having differential members adapted to be moved different amounts according to the value of the digit to be set up, said differential members having different points of actuation, and figure keys for operating said differential members, said differential members being shiftable to nine different positions relatively to said keys to thereby cause said keys to produce nine different quantities of motion of said differential members.

3. A multiplying machine having differential members having eighty-one points of actuation capable of producing nine different quantities of movement, and figure keys for operating said differential members, said differential members being movable to nine different positions to thereby present the different points of actuation to the figure keys.

4. A multiplying machine having actuators for operating the computing mecha-

nism, differential members adapted to oscillate and to shift bodily for the purpose described, means for operating said differential members, and means for shifting said differential members.

5. A multiplying machine having figure keys, differential actuators adapted to be actuated thereby, said differential actuators being shiftable to different positions relatively to said figure keys, to be contacted thereby at different points depending upon the value of the multiplier and means for shifting said differential actuators.

6. A multiplying machine having figure keys, differential members adapted to be actuated thereby, said differential members being shiftable to different positions relatively to said figure keys, to be contacted thereby at different points depending upon the value of the multiplier and means for shifting said differential members, said differential members appearing in pairs, one pair for each ordinal place in the machine, except the highest and lowest.

7. A multiplying machine having figure keys, differential members adapted to be actuated thereby, said differential members being shiftable to different positions relatively to said figure keys, to be contacted thereby at different points depending upon the value of the multiplier and means for shifting said differential members, said differential members appearing in pairs, one pair for each ordinal place in the machine, except the highest and lowest, one differential member in a pair being for the units and the other for the tens of the partial products, and a single figure key being adapted to operate a pair of differential members.

8. A multiplying machine having figure keys, differential members adapted to be actuated thereby, each of said differential members having two kinds of movement, one kind for actuating the computing mechanism and the other kind for changing the position of the differential members relatively to the figure keys to be actuated thereby at different points depending upon the value of the multiplying digit.

9. A multiplying machine having nine figure keys for each ordinal place in the machine, a pair of differential members for each ordinal place in the machine, except the highest and the lowest, each pair of differential members being adapted to be operated by all of the keys in the respective ordinal place, and said differential members having eighty-one points of actuation and being shiftable to nine different positions for presenting different ones of said points of actuation to said keys.

10. In a multiplying machine, a row of nine figure keys in each ordinal place, a pair of differential members for each row adapted to be operated by all of the figure

4
keys in said row, there being nine different points of actuation on each differential member for each figure key and said figure keys each being adapted to operate two differential members, and factor keys for causing said differential members to present different points of actuation to said figure keys.

5 11. A multiplying machine having figure keys and differential bars adapted to be contacted thereby, said bars being slideable relatively to said figure keys to thereby present different points of contact to the keys depending upon the value of the multiplier, there being two differential members for 15 each order in the machine except the highest and lowest.

10 12. A multiplying machine having oscillatory differential one-piece members having different surfaces of actuation formed thereon, and figure keys for oscillating said differential members, said differential members being slideable to nine different positions relatively to said keys for presenting different surfaces of actuation thereto, and factor 25 keys for causing the sliding of said differential members.

13. A multiplying machine having actuators for actuating the computing mechanism, two differential members movably mounted on each of said actuators, except the highest and lowest, and figure keys adapted to actuate two differential members, one on one actuator and one on the adjacent actuator.

35 14. A computing machine having actuators for actuating the computing mechanism, two differential members movably mounted on each of said actuators, except the highest and lowest, figure keys adapted 40 to actuate two differential members, one on one actuator and one on the adjacent actuator, and means for moving said differential members relatively to said actuators for the purpose described.

45 15. In a multiplying machine the combination of actuators for actuating the computing mechanism, a units and a tens differential member on each of the actuators, except the highest and lowest, the lowest actuator having a units differential member and the highest having a tens differential member, figure keys adapted to contact the units differential member on one actuator and the tens differential actuator on the next higher 50 actuator, factor keys and connections between said factor keys and said differential members whereby the depression of a factor key produces a movement of the differential members to present different points of actuation of the differential members to the respective figure keys.

60 16. A multiplying machine having nine figure keys running from 1 to 9 in each ordinal place in the machine, a rotary actuator 65 for each ordinal place in the machine, said

actuators being adapted to operate the computing mechanism, a units and a tens differential member slidingly mounted upon each actuator, except the highest and lowest actuator, the lowest actuator having a units differential member, and the highest having a tens differential member, one figure key being adapted to operate the units differential member on one actuator and the tens differential member of the actuator of next 70 higher order, eight factor keys running from 2 to 9, and connections between said factor keys and all of said differential members whereby any factor key may shift all of the differential members upon the respective actuators to thereby present different points of actuation on the differential members to the figure keys.

75 17. In a machine of the character described, the combination of a series of sets of denominational keys, and actuators one for each set of keys and operable thereby and having a plurality of differentiated abutments for each key of the set, with provisions for relative adjustment between the actuator and the keys to vary the abutments 80 presented to the latter.

85 18. In a machine of the character described, the combination of a series of sets of denominational keys, and actuators one for each set of keys and operable thereby and having a plurality of differentiated abutments for each key of the set, with provisions for relative adjustment between the actuator and the keys to vary the abutments 90 presented to the latter; higher order actuators also having differentiated abutments for next lower order keys.

95 19. In a machine of the character described, the combination of a series of sets of denominational keys, the keys in each set having different extents of movement, a series of actuators one for each set of keys and operable thereby, and means for varying the point in its movement at which each key engages the actuator.

100 20. In a machine of the character described, a series of actuators, a series of sets of keys, one set for each actuator, the keys of each set made movable to different extents, and means carried by each actuator for varying the point at which it is engaged by each of the keys of the set with which it is associated.

105 21. In a machine of the class described, 120 the combination of levers; a set of keys for each lever; and bars slideable on the levers and having differentiated abutments for the keys.

110 22. In a machine of the class described, 125 the combination of levers; a set of keys for each lever; bars slideable on the levers and having differentiated abutments for the keys, and means for setting the bars.

120 23. In a machine of the class described, 130

the combination of levers; a set of keys for each lever; bars slideable on the levers and having differentiated abutments for the keys, and a set of keys and connections 5 therefrom to said bars for variously setting the latter.

In witness whereof, I have hereunto sub-

scribed my name in the presence of two witnesses.

JOHN BRICKEN.

Corrections in Letters Patent No. 1,119,061.

It is hereby certified that in Letters Patent No. 1,119,061, granted December 1, 1914, upon the application of John Bricken, of Chicago, Illinois, for an improvement in "Calculating-Machines," errors appear in the printed specification requiring correction as follows: Page 1, line 70, for the word "ordinary" read *ordinal*; page 4, line 116, strike out the words "carried by" and insert the words *associated with*; and that the said Letters Patent should be read with these corrections therein that the same may conform to the record of the case in the Patent Office.

Signed and sealed this 26th day of January, A. D., 1915.

[SEAL.]

R. F. WHITEHEAD,

Acting Commissioner of Patents.
